G. RICKELMANN

AEROPLANE

Filed Sept. 7, 1927

UNITED STATES PATENT OFFICE.

GUSTAV RICKELMANN, OF HALEDON, NEW JERSEY.

AEROPLANE.

Application filed September 7, 1927. Serial No. 217,960.

Aeroplanes have been proposed in which a fore-and-aft-extending substantially cylindrical hollow body or structure forms the lifting medium or a part of such medium of 5 the machine. According to this invention, I utilize such a structure and combine therewith plane or lifting surfaces placed at front and rear of the structure, preferably within it, at different elevations and inclined. The object 10 is to increase the lifting power of such a machine and also its inherent stability, which latter will follow if the plane-forming elements are within the cylindrical structure as chords thereof and connect it as braces.

15 In the drawing,
Fig. 1 is a side elevation of the invention;
Fig. 2 is a front elevation; and
Fig. 3 a view illustrating, more or less 20 diagrammatically, certain direction controlling devices and their controlling means.

The hollow cylindrical structure is shown at 1 and as having spiders 2 composed of radial links. These spiders reinforce the tubular or cylindrical wall of the structure 1 25 and afford support for the motor 3, which may be of the rotary type, the propeller being indicated at 4; this latter, however, is not material to the invention, since any other type of motor and any other means for supporting 30 it may be resorted to.

Two sets of rigid or substantially inflexible planes are shown, one, 5 at the forward end, and the other, 6, at the rear end, of the structure 1. In each set the planes are arranged 35 horizontally as viewed lengthwise of the machine and one above another and spaced from each other and they are forwardly uptilted, i. e., in the forward direction, or to the left in Fig. 1. They form walls lying in chords of 40 and are rigidly secured to the cylindrical wall of the structure, so that they assist in bracing or reinforcing the latter.

At the rear edge of each plane 5 or 6 is arranged, pivoted to said edge and its own forward edge, a pair of plane-extensions 5^a 6^a each of which functions and is useful substantially the same as the aileron of the plane or wing of an ordinary aeroplane.

For changing the course of the machine up 50 or down there is a horizontal rudder 8 pivotally supported on a horizontal shaft 7 fixed at its ends in the cylindrical structure. For changing the course of the machine laterally there is the vertical rudder 9 in two parts,

one above and the other below rudder 8, pivotally supported on a vertical shaft 10 fixed at its ends in said structure. Manipulation of these Rudders makes it possible to cause the machine to travel in any direction, as will be apparent.

Suitably suspended from the cylindrical structure may be a fuselage or cabin 11 having running gear 12 adapting the machine for running on the ground at the start and finish of a flight.

Shifting of the plane-extensions and the Rudders may be accomplished as follows: Around pulleys 13 in the structure 1 and the fuselage is a wire, rope or equivalent 14 which is attached to the horizontal rudder 8 in a manner to form therewith an endless control, the lever or handle for shifting which is shown at 15 fulcrumed within the fuselage. Substantially similar means may be employed for shifting the vertical Rudders and the forward and rearward plane-extensions, in which in Fig. 3 16 is the wire, rope or equivalent for the vertical rudder, 17 that for the forward set of plane-extensions at one side of the machine, and 18 that for the rearward set 80 of plane-extensions at said side of the machine, the connections of course being such in the case of the parts of the vertical rudder and that of the members of each set of superposed plane-extensions that they move in unison.

The placing of the planes 5 and 6 within the cylindrical body 1 so that they span it horizontally and brace it contributes to the strength and stability of the whole structure 90 formed by said body and planes. Placing said planes within said body also results in the air being confined within said body to act with full effect on the planes, i. e., without losses or disturbing influences incident to the 95 action of the propeller and extraneous causes, so that the lifting action of these planes is a factor that is constant unless, only, the air pressure developed against these planes in the substantially longitudinal direction changes 100 on account, for example, of change in speed of the motor.

I claim:

1. An aeroplane including a hollow cylindrical body arranged horizontally and 105 having a forward and a rear end and planes arranged within said body so as to stand horizontally as viewed lengthwise and a rear

plane-extension for each plane pivotally movable on a horizontal axis at the forward part of such plane-extension.

2. An aeroplane including a hollow cylindrical body arranged horizontally and having a forward and a rear end, spaced forward and rear planes arranged and held within said body so as to stand horizontally as

viewed lengthwise of the same, a plane-extension for each plane pivotally movable on a horizontal axis at the forward part of such plane-extension, and means to shift each plane-extension on its pivot. 10

In testimony whereof I affix my signature.

GUSTAV RICKELMANN.
